CLAIM

I claim the ornamental design for a guitar case, as shown and described.

DESCRIPTION

FIG. 1 is a front perspective view of the guitar case, showing my new design;

FIG. 2 is a front view thereof;

FIG. 3 is a rear view thereof;

FIG. 4 is a left side view thereof;

FIG. 5 is a right side view thereof;

FIG. 6 is a left side view thereof;

FIG. 7 is a right side view thereof;

FIG. 8 is a rear side-front portion view thereof;

FIG. 9 is a front perspective view of the guitar case showing me design, according to a second embodiment;

FIG. 10 is a front view thereof;

FIG. 11 is a rear view thereof;

FIG. 12 is a left side view thereof;

FIG. 13 is a right side view thereof;

FIG. 14 is a left side view thereof;

FIG. 15 is a right side view thereof; and,

FIG. 16 is a rear side-front portion view thereof.

The broken lines in the drawings of the guitar case are for showing the portion of the guitar case and form no part of the claimed design.

1 Claim, 12 Drawing Sheets
